US00D828856S

(12) **United States Design Patent** (10) Patent No.: **US D828,856 S**
(45) Date of Patent: **** Sep. 18, 2018**

(54) **AUDIO INPUT/OUTPUT DEVICE**

(71) Applicant: **Amazon Technologies, Inc.**, Seattle, WA (US)

(72) Inventors: **Heinz-Dominik Langhammer**, San Francisco, CA (US); **Marc Rene Walliser**, San Francisco, CA (US); **Robert Brian Curtis**, San Francisco, CA (US); **Christopher Green**, San Francisco, CA (US)

(73) Assignee: **Amazon Technologies, Inc.**, Seattle, WA (US)

(**) Term: **15 Years**

(21) Appl. No.: **29/620,880**

(22) Filed: **Dec. 29, 2016**

Related U.S. Application Data

(63) Continuation of application No. 29/543,578, filed on Oct. 26, 2015, now Pat. No. Des. 778,956, which is a (Continued)

(57) **CLAIM**

The ornamental design for an audio input/output device, as shown and described.

DESCRIPTION

FIG. 1 is a perspective view of an audio input/output device; FIG. 2 is another perspective view of the audio input/output device of FIG. 1;

FIG. 3 is a front view of the audio input/output device of FIG. 1;

FIG. 4 is a back view of the audio input/output device of FIG. 1;

FIG. 5 is a left-side view of the audio input/output device of FIG. 1, the right-side view of the audio input/output device being a mirror image of the left-side;

FIG. 6 is a top view of the audio input/output device of FIG. 1; and,

FIG. 7 is a bottom view of the audio input/output device of FIG. 1.

(Continued)

The broken lines are directed to unclaimed portions and form no part of the claimed design.

1 Claim, 6 Drawing Sheets

Related U.S. Application Data

continuation of application No. 29/503,695, filed on Sep. 29, 2014, now Pat. No. Des. 744,541.
